ROTATABLE PACKER

John W. MacClatchie, Los Angeles, Calif., assignor to MacClatchie Manufacturing Company of California, Compton, Calif., a corporation of California

Application December 28, 1936, Serial No. 117,857

5 Claims. (CL. 255—1)

This invention is a packer for sealing between a well string and surrounding well casing, and it is the object of the invention to adapt the packer for rotation with the well string, thereby particularly adapting it for use in connection with a well string of that type which forms a usual drill string for rotary drilling, with the rotatable packer adapted for sealing engagement with any portion of the well string, and adapted to maintain the seal while the well string is being moved through the packer.

The invention is thus particularly applicable to drilling under pressure, in that the packer is readily deformable for sealing engagement at the kelly of a drill string and is rotatable with the kelly while maintaining the seal so as to form a drilling head permitting rotation and longitudinal movement of the drill string while sealing the well against escape of pressure, and the packer is adapted to yield sufficiently to permit passage of coupling collars and the like while maintaining the seal and is deformable to conform to and seal off at the different portions of a drill string which are of varying size and cross-sectional contour, so as to permit the drill string being inserted and withdrawn while sealing the well against escape of pressure. The invention thus provides a combination drilling head and blowout preventer, sealing the well at the kelly while drilling, and also sealing the well while the drill string is being inserted and withdrawn, and thus maintaining a seal at all times and against any well pressure which may be encountered, and which may be simply a desired pressure maintained in the well for drilling under pressure or which may be any excessively high pressure resulting from increase in the formation pressure of the well.

It is a further object of the invention to adapt the rotatable packer for sealing engagement responsive to pressure fluid, with the pressure fluid supplied from a source external of the well so that it may be controlled for maintaining such sealing engagement by the packer as will prevent escape of well pressure while permitting movement of a well string through the packer, and with the mounting which adapts the packer for rotation including a connection whereby the pressure fluid may be supplied to the rotatable packer from a stationary conduit which leads to an external source of supply.

It is a still further object of the invention to provide a mounting for the rotatable packer adapting it for lateral play with relation to the stationary well casing, for alining the packer

with the well string irrespective of usual alinement of the well string in the well casing, with the connection which supplies pressure fluid from an external source maintaining communication irrespective of such lateral play of the 5 rotatable packer.

Further objects of the invention will be readily understood from the following description of the accompanying drawing, in which:

Fig. 1 is a side elevation of the invention, partly 10 in axial section.

Fig. 2 is a transverse section on the line 2—2 of Fig. 1.

The packer is adapted for sealing engagement 15 with a well string which is received in usual well casing, and is adapted for rotation with the well string. For this purpose the packer is preferably mounted in a housing, for rotation with the housing which is preferably journaled on a body 2 which may be mounted on the well casing 3 by 20 a threaded connection 4. The body 2 has a bore 5 forming a prolongation of the bore of the well casing, with lateral outlets 6 preferably communicating with the bore 5.

In the illustrated embodiment of the invention 25 the housing forms an annular chamber of greater diameter than the bore of the well casing and adapted to receive the packer; and the packer is an annular packer having a bore 30 adapted for contraction to engage a well string which extends through the housing and into the well bore, or adapted for expansion so as to form an unobstructed prolongation of the bore of the well casing.

The packer and its housing may be of the type 35 disclosed in my copending application Ser. No. 112,745, filed November 25, 1936; and as an instance of this arrangement the housing may be a two-part housing 10—11 having its parts 40 flanged as shown at 12 and connected by bolts 13, with packing 14 preferably provided at the abutting surfaces of the flanges. The assembled housing forms an annular chamber or enlargement of appreciably greater diameter than the 45 bore 5, and annular flanges 15 project longitudinally of the housing and toward one another from the respective ends of this annular enlargement, with the bores 16 of the flanges preferably substantially in prolongation of the bore 5, and 50 with the flanges preferably integral with the housing. The assembled housing has an inner surface 17 defining its annular enlargement, preferably curving inwardly toward the respective ends of the housing and merging into the 55

radially outer surfaces of the longitudinally extending annular flanges 15.

The packer 20 which is mounted in the annular enlargement of the housing is shown as an annulus of resilient packing matter such as rubber or the like. This annulus has an outer periphery longitudinally curved to correspond to the curved surface 17, and has a bore 22, counterbored at its ends as shown at 23, so that when the resilient 5 packing annulus is mounted in the housing, and is in its normal position as shown at Fig. 1, its bore 22 is substantially in prolongation of the bores 16 of the annular flanges 15, with these annular flanges extending into the counterbores 10 23 at the ends of the packing annulus, and with the walls of the counterbores preferably appreciably spaced radially outwardly from the flanges 15.

The outer periphery of the packer is annularly recessed medially of the length of the packer as 20 shown at 24, and this recess is preferably undercut at its upper and lower sides to form lips 25. Pressure fluid is exerted in the annular recess 24 for contracting the bore of the packer to its operative 25 sealing position which is shown by broken lines at Fig. 1, and the fluid pressure may be supplied via a conduit 26 which is preferably formed in the housing 11 and which communicates with a stationary supply conduit 27 which leads to any suitable 30 external source of pressure fluid. The pressure fluid is preferably that of a liquid such as water, and the supply conduit 27 is provided with a suitable valvular control (not shown) whereby pressure fluid may be conducted in the annular 35 recess 24 for operatively contracting the bore of the packer, or may be exhausted from the annular recess to permit the resiliency of the packer returning it to its normal inoperative position.

The pressure fluid which is supplied to the 40 annular recess 24, flexes the lips 25 for sealing contact with the curved surface 17, and then swings the longitudinal end portions of the packer so that they move along the curved surface 17 and annularly contract in accordance with the inherent 45 compressibility of the packer material, until arrested by their abutment against the flanges 15. The pressure fluid then radially inwardly expands that portion of the packer which defines its bore 22, so that for some appreciable length medially 50 thereof the bore of the packer radially contracts for sealing around any well string extending through the bore of the packer and into the bore of the well casing.

The well string which is sealed off may be a 55 usual drill string comprising coupled lengths of drill pipe 30, with a kelly 31 which is preferably of usual polygonal cross-sectional contour connected to the upper end of the drill pipe by a coupling 32. When the bore of the packer is operatively contracted it is adapted for such distortion as to seal around the drill string at any portion thereof, e. g. either at the tubular drill pipe or its polygonal kelly, or at the enlarged couplings which connect the various sections of the drill string, or where 60 the different diameters and cross-sectional contours of the drill string meet one another, and the packer is adapted to maintain the seal by readily conforming to the changing diameter and cross-sectional contour of different portions of the drill 65 string, while the latter is moved longitudinally 70 through the packer.

When the packer seals against the cross-sectionally polygonal kelly 31, rotation of the drill string rotates the packer with the kelly while 75 permitting longitudinal movement of the kelly

through the packer, and the housing 10-11 turns with the rotating packer, being journaled on the body 2. As an instance of this arrangement the lower end of the housing 11 may be flanged as shown at 40, with this flange journaled on a cooperating bearing flange 41 of the body 2, and a longitudinally projecting annular flange 42 at the outer periphery of the flange 41 may support a diametrically split flange 43 which overlies the flange 40. Anti-friction bearings are preferably 10 provided between the flanges 40-41 as shown at 44 between the flanges 40-43 as shown at 45, and between the peripheral surfaces of the flanges 40-42 as shown at 46.

The housing 10-11 is thus adapted for rotation 15 relative to the body 2 while securely held against longitudinal displacement, and is preferably free for some lateral play so that the packer 20 which is mounted in and rotates with the housing may align with the drill string or other object which it 20 is to pack off, irrespective of any misalignment of the drill string in the well casing 3. For this purpose the flange 40 and the surrounding longitudinally projecting annular flange 42 are of such relative diameter that a radial space is provided 25 between their peripheral surfaces when the housing 10-11 is concentric with the bore of the well casing, thereby permitting lateral play of the rotatable housing, limited by the periphery of the flange 40 engaging the anti-friction bearings 46. 30

The conduit 26 which is formed in the housing 11, maintains communication with the stationary conduit 27 during rotation of the housing 10-11, irrespective of lateral play of the rotatable housing. As an instance of this arrangement the conduit 26 communicates with an annular channel 50 in the bearing face of the flange 40, and the conduit 27 communicates with a conduit 27a which is formed in the flange 41 and which extends to the bearing face of said flange in alignment with the 40 channel 50. The channel 50 is of a width to maintain communication with the conduit 27a irrespective of lateral play of the housing 10-11.

Suitable packing is preferably provided between the rotating and non-rotating elements, and may 45 comprise hydraulic packing 51 between the flanges 40-41, preferably adjacent and operatively expanded by pressure in the bore 5-16, together with a split packing ring 52 at the inner periphery of the flange 43 and operatively engaging the flange 40. Hydraulic packing is preferably also provided between the flanges 40-41, at the respective sides of the channel 50 so as to prevent escape of the pressure fluid which is supplied via the conduit 27a, and is shown at 53, adapted for 55 operative expansion by the pressure fluid in the conduit 27a.

The invention thus provides means for packing off any well string which may be received in the well casing 3, with the packer adapted for sealing 60 engagement responsive to external pressure fluid and adapted to pack off any portion of the well string and to maintain the seal while permitting movement of the well string through the packer, with the packer adapted for rotation with the well 65 string which it packs off and also adapted for lateral play relative to the stationary well casing, while maintaining a connection whereby pressure fluid may be supplied to the rotatable packer from a stationary conduit leading to an external source 70 of supply.

I claim:

1. In combination, a well casing adapted to receive a well string for reciprocation and/or rotation therein, a structure mounted on said casing

and having an opening therethrough in substantial continuation of the well casing bore, said structure forming at its upper side an annular supporting base, a housing for a packer having a supporting flange around its lower side, said annular base having bearing surfaces engaging opposite faces of said housing flange for securing the flange and the housing against displacement axially but permitting free rotation of the housing on the base around the casing bore as an axis there being anti-frictional bearings at each of said bearing surfaces, said housing forming an enlarged diameter continuation of the casing bore, an annular packer of the pressure fluid expansible type mounted and confined in said housing against axial displacement and having a bore therethrough in continuation of the casing bore, said packer being adapted to surround a well string extending therethrough and in its non-sealing and inactive position being completely disengaged and free from a well string whereby said packer remains stationary during rotation of the well string, said packer being projectible by pressure fluid into a position engaged with and sealing completely around the well string whereby rotation of the latter rotates said packer and housing as a unit, with the packer in sealing engagement with the well string, a pressure fluid supply port in the upper face of said supporting base, an annular pressure fluid chamber around said flange opening through the lower face thereof, in alignment with said supply port whereby said port is in constant communication with said chamber as the housing is rotated on said base, and said housing being provided with a pressure fluid passage from said annular chamber to the expansible packer mounted in said housing for supplying pressure fluid to said packer to project the same into sealing engagement with the well string.

2. In combination, a well casing adapted to receive a well string for reciprocation and/or rotation therein, a structure mounted on said casing and having an opening therethrough in substantial continuation of the well casing bore, the upper side of said structure providing an annular supporting base, a housing for a packer having a radially disposed supporting flange around its lower side, said annular base having bearing surfaces engaging opposite faces of said housing flange and a bearing surface normally spaced from and around the peripheral face of said flange for securing the flange and housing against displacement axially but permitting lateral adjustment of the flange and housing relative to the base, and the casing bore, there being anti-frictional bearings at each of said bearing surfaces whereby said housing is adapted for free rotation on the base around the casing bore as an axis, said housing forming an enlarged diameter continuation of the casing bore, an annular packer of the pressure fluid expansible type mounted and confined in said housing against axial displacement and having a bore therethrough in continuation of the casing bore, said packer being adapted to surround a well string extending therethrough and in its non-sealing and inactive position being completely disengaged and free from a well string whereby said packer remains stationary during rotation of the well string, said packer being projectible by pressure fluid into a position engaged with and sealing completely around the well string whereby rotation of the latter rotates said packer and housing as a unit, said packer being provided

with a pressure fluid recess there around for receiving pressure fluid to expand the packer, a pressure fluid supply port in said supporting base, an annular pressure fluid chamber around said housing supporting flange in constant communication with said supply port as the flange is rotated with the housing, and said housing being provided with a pressure fluid passage therein from said annular chamber of the flange to and in communication with the pressure fluid recess in said packer.

3. In combination, a well casing adapted to receive a well string for reciprocation and/or rotation therein, a structure mounted on said casing and having an opening therethrough in substantial continuation of the well casing bore, said structure forming at its upper side an annular supporting base, a housing for a packer having a supporting flange around its lower side, said annular base having bearing surfaces engaging opposite faces of said housing flange for securing the flange and the housing against displacement axially but permitting free rotation of the housing on the base around the casing bore as an axis, there being anti-frictional bearings at each of said bearing surfaces, said housing forming an enlarged diameter continuation of the casing bore, an annular packer of the pressure fluid expansible type mounted and confined in said housing against axial displacement and having a bore therethrough in continuation of the casing bore, said packer being projectible by pressure fluid into a position sealing completely around the well string, said packer and housing being rotatable as a unit with the well string, a pressure fluid supply port in the upper face of said supporting base, an annular pressure fluid chamber around said flange opening through the lower face thereof in alignment with said supply port whereby said port is in constant communication with said chamber as the housing is rotated on said base, and said housing being provided with a pressure fluid passage from said annular chamber to the expansible packer mounted in said housing for supplying pressure fluid to said packer to project the same into sealing engagement with the well string.

4. In combination, a well casing adapted to receive a well string for reciprocation and/or rotation therein, a structure mounted on said casing and having an opening therethrough in substantial continuation of the well casing bore, the upper side of said structure providing an annular supporting base, a housing for a packer having a radially disposed supporting flange around its lower side, said annular base having bearing surfaces engaging opposite faces of said housing flange and a bearing surface normally spaced from and around the peripheral face of said flange for securing the flange and housing against displacement axially but permitting lateral adjustment of the flange and housing relative to the base and the casing bore, there being anti-frictional bearings at each of said bearing surfaces whereby said housing is adapted for free rotation on the base around the casing bore as an axis, said housing forming an enlarged diameter continuation of the casing bore, an annular packer of the pressure fluid expansible type mounted and confined in said housing against axial displacement, and having a bore therethrough in continuation of the casing bore, said packer being projectible by pressure fluid into a position sealing completely around the well string and being rotatable with

said housing as a unit, by rotation of the well string, said packer being provided with a pressure fluid recess there around for receiving pressure fluid to expand and project the packer, a 5 pressure fluid supply port in said supporting base, an annular pressure fluid chamber around said housing supporting flange in constant communication with said supply port as the flange is rotated with the housing, and said housing 10 being provided with a pressure fluid passage therein from said annular chamber of the flange to and in communication with the pressure fluid recess in said packer.

5. In combination, a well casing adapted to 15 receive a well string for reciprocation and/or rotation therein, a structure mounted on said casing and having an opening therethrough in substantial continuation of the well casing bore, the upper side of said structure providing an 20 annular supporting base, a housing for a packer having a radially disposed supporting flange around its lower side, said annular base having bearing surfaces engaging opposite faces of said housing flange and a bearing surface normally 25 spaced from and around the peripheral face of said flange for securing the flange and housing against displacement axially but permitting lateral adjustment of the flange and housing relative to the base and the casing bore, whereby

said housing is adapted for free rotation on the base around the casing bore as an axis, said housing forming an enlarged diameter continuation of the casing bore, an annular packer of the pressure fluid expansible type mounted and 5 confined in said housing against axial displacement and having a bore therethrough in continuation of the casing bore, said packer being adapted to surround a well string extending therethrough and in its non-sealing and inactive 10 position being completely disengaged and free from a well string whereby said packer remains stationary during rotation of the well casing, said packer having a pressure fluid recess there around for receiving pressure fluid to project the 15 packer into position engaged with and sealing completely around the well string whereby rotation of the latter rotates said packer and housing as a unit, said housing supporting flange being provided with a fluid pressure chamber 20 therein, said housing being provided with a pressure fluid passage therein from said chamber to and in communication with the pressure fluid recess in said packer, and means on said supporting base for supplying pressure fluid to the 25 pressure fluid chamber of said housing supporting flange in all positions of the latter.

JOHN W. MACCLATCHIE.
